(57) **CLAIM**

The ornamental design for a nozzle assembly for a helicopter landing pad, as shown and described.

DESCRIPTION

FIG. 1 is an upper perspective view of the nozzle assembly for a helicopter landing pad showing my design;

FIG. 2 is a front elevation view thereof, a back elevation view, a side elevation view and an opposite side elevation view being identical;

FIG. 3 is a top plan view thereof;

FIG. 4 is a bottom plan view thereof; and,

FIG. 5 is another perspective view thereof, showing placement in a landing pad in broken lines.

The nozzle assembly fits in a landing pad floor, shown in broken lines. The landing pad floor is environment only and forms no part of the claimed design.
